UNITED STATES PATENT OFFICE.

ROBERT ALEXANDER SNODGRASS, OF TORONTO, ONTARIO, CANADA, ASSIGNOR TO MERGENTHALER LINOTYPE COMPANY, A CORPORATION OF NEW YORK.

TYPOGRAPHICAL MACHINE.

Application filed December 4, 1923. Serial No. 678,493.

To all whom it may concern:

Be it known that I, ROBERT ALEXANDER SNODGRASS, a subject of the King of Great Britain, and a resident of Toronto, Province of Ontario, and Dominion of Canada, have invented a new and useful Improvement in Typographical Machines, of which the following is a specification.

This invention relates to typographical machines such as linotype machines of the general organization represented in Letters Patent of the United States to O. Mergenthaler, No. 436,532, wherein circulating matrices are released from a magazine in the order in which their characters are to appear in print, and then assembled in line together with spacers, the composed line transferred to the face of a mold, and the mold filled with molten metal to form a slug or linotype against the matrices which produce the type characters thereon. After casting, the line is carried upward and shifted into what is commonly known as the upper transfer channel, where the matrices are lifted from the line and delivered to a distributing mechanism which returns them to the magazine or magazines from which they started. The spacers, which remain suspended upon rails in the transfer channels, are then acted upon by a transfer device having a hook-shaped finger which draws the spacers along the supporting rails into their storage magazine. As the transfer device is thus constructed, it frequently happens, particularly when full length or 30 em lines are being handled, that the spacers become dislodged from or twisted out of place on the supporting rails and thereby interfere with the proper operation of the machine, or cause damage to the parts.

The present invention is intended to obviate the foregoing difficulties and contemplates the provision of means whereby the spacers, without regard to their number or position, are first brought together or compacted and then retained in such relation during their delivery to the magazine. In the preferred embodiment illustrated, the hook-shaped finger, above referred to, is provided with a yielding jaw which is adapted, during the outward movement of

the transfer device, to engage a row of spacers at the right and push them together and thereafter close in upon the spacers to retain them in compact relation during the delivery movement of the transfer device.

In the accompanying drawings, the invention has been shown only in preferred form and by way of example, and as applied to the specific style of machine mentioned, but obviously many changes and variations may be made therein, and in its mode of application, which will still be comprised within its spirit. It is to be understood, therefore, that the invention is not limited to any specific form or embodiment, except in so far as such limitations are specified in the claims.

In the accompanying drawings:

Fig. 1 is a front elevation of a portion of a linotype machine equipped with the present improvements;

Fig. 2 is an enlarged view of the improved transfer device, partly in section, indicating its action in picking up and delivering a row of spacers;

Fig. 3 is a vertical transverse section taken on the line 3—3 of Fig. 2;

Fig. 4 is a detail plan view, partly broken away, of the improved transfer finger; and

Fig. 5 is a detail section taken on the line 5—5 of Fig. 4.

Referring to Fig. 1, the matrices X are released from their magazine A and the spacers Y from their magazine A¹ by keyboard mechanism (not shown) and composed in line in the assembler B, in the usual way. The assembler is then manually elevated and trips the delivery slide C, which thereupon shifts the composed line through the intermediate channel D into the first elevator E. The elevator E then descends with the line to the casting position, and, after the slug is cast, rises to its uppermost position, where a slide F, operated by a lever F¹ pushes the line into the upper transfer channel G. During this transfer of the line, the matrices X pass onto the second elevator bar H, which later carries them upwardly for distribution, while the spacers Y are supported by their projecting ears upon a pair of rails G¹ within the channel G. After the matrices have been car-

ried upward, the spacers, which remain behind, are then raked into their magazine A¹ by a transfer finger J formed at its free end with a depending jaw J¹ and provided with 5 a rearwardly extending pin J² which supports it in proper engaging relation to the spacers. The finger J is carried by an operating lever J³ pivoted to the machine frame, as at J⁴, and loosely connected near 10 its lower end by means of a link F² to the slide-operating lever F¹, which latter is keyed or otherwise secured to a transverse rock shaft F³. This shaft F³ extends rearwardly and carries an arm F⁴ provided with 15 a roller F⁵ tracking upon a face cam K against which it is held by a spring F⁶. Normally, the parts just described occupy the positions indicated by dotted lines in Fig. 1, but during the rotation of the cam 20 K, the slide F and finger J are brought together, as shown in full lines, the jaw J¹ being bevelled off at one side so as to pass over the tops of the spacers and drop in behind the row. As the cam K completes its rotation, 25 the parts are restored to their normal position and the spacers thereby transferred by the finger J to their magazine A¹.

The parts so far described and their mode of operation are or may be substantially the 30 same as set forth in the Mergenthaler patent above referred to, or as presented in the commercial linotype machine. Ordinarily, the spacers, in being transferred from the channel G, are moved together from the left 35 by the slide F before they are engaged by the transfer finger J, provided the line is a short one or one wherein the spacers occupy a position to the left of the meeting point of those parts. However, when the line is 40 a long one, some of the spacers occupy a position beyond the reach of the slide F, and such spacers are therefore subject to displacement or twisting, either when engaged by the finger J as the latter passes over them 45 in its outward movement, or during the delivery movement.

As before stated, the present invention is intended to obviate the foregoing objections and contemplates the provision of means to 50 keep the spacers from swinging out of position under the conditions stated. To this end, the transfer finger J is provided on its under side with a further right-hand jaw J⁵ mounted to slide horizontally on a guide plate J⁶ fastened to the finger. A compression spring J⁷, engaging behind the said jaw, holds it yieldingly against a stop or shoulder J⁸ of the plate J⁶. The two jaws J¹ and J⁵ are thus normally held a certain distance 55 apart in order to permit the jaw J⁵ to function in the desired manner. The action of the parts will now be clear. As best shown in Fig. 2, when the slide F and finger J approach each other, those spacers standing 60 to the left of their meeting point are pushed 65

toward the right by the slide F, while those spacers standing to the right of such meeting point are pushed toward the left by the jaw J⁵, the spacers being thus brought together in compact relation. If need be, the 70 jaw J⁵ will yield against the action of its spring J⁷ to permit the slide F and finger J to come together, at which time the left-hand jaw J¹ will have passed over and dropped behind the first spacer of the row 75 in readiness for the transfer movement which immediately takes place. As the transfer movement begins, the slide F recedes and the jaw J⁵ moves over under the action 80 of the spring J⁷ and grips the spacers between it and the fixed jaw J¹, thereby retaining the spacers in compact relation throughout the delivery movement, see the dotted-line showing in Fig. 2.

Having thus described my invention, what 85 I claim is:

1. In a typographical machine, the combination of a spacer magazine, a transfer device for delivering the spacers thereto, and means associated with the said device to retain the spacers in compact relation during 90 their delivery to the magazine.

2. In a linotype machine, the combination of a spacer magazine, a transfer channel 95 provided with spacer supporting rails leading to the magazine, a transfer device for carrying the spacers along said rails to the magazine, and means associated with said transfer device to hold the spacers in compact relation during their delivery to the 100 magazine.

3. In a typographical machine, the combination of a spacer magazine, a transfer device for delivering the spacers thereto, and means whereby the spacers are brought together during the outward stroke of the transfer device and retained in compact relation during the delivery stroke of said transfer device.

4. In a typographical machine, the combination of a spacer magazine, a transfer device for delivering spacers to the magazine, and means carried by said device and automatically adjustable to accommodate different numbers of spacers and hold them in compact relation during their delivery to the magazine.

5. In a typographical machine, the combination of a spacer magazine, and a transfer device for delivering spacers thereto, the said device having right- and left-hand jaws between which the spacers are retained in compact relation during their delivery to the magazine.

6. In or for a linotype machine, a spacer transfer finger having right- and left-hand spacer-engaging jaws, one fixed and the other spring-pressed toward the fixed jaw, for the purpose described.

7. In or for a linotype machine, a spacer 130

transfer finger provided with two spacer- transfer finger J, the latter being provided
engaging jaws, one fixed and the other with the fixed jaw J^1 and the spring-pressed
spring-pressed toward the fixed jaw, and a jaw J^2 , all operating substantially in the 10
stop to limit the approaching movement of manner set forth.

⁵ said spring-pressed jaw.

8. In a linotype machine, the combination of the line transfer slide F, and the spacer

In testimony whereof I hereunto set my hand this second day of November, 1923.

ROBERT ALEXANDER SNODGRASS.
